UNITED STATES PATENT OFFICE.

SIMEON C. LAWLOR, OF CHICAGO, ILLINOIS.

WRINGING APPARATUS.

Application filed September 13, 1919. Serial No. 323,507.

To all whom it may concern:

Be it known that I, SIMEON C. LAWLOR, a citizen of the United States, residing at Chicago, in the county of Cook and State 5 of Illinois, have invented certain new and useful Improvements in Wringing Apparatus; and I do hereby declare the following to be a full, clear, and exact description of the invention, such as will enable others 10 skilled in the art to which it appertains to make and use the same.

This invention relates to improvements in scrubbing apparatus, and more particularly to wringing attachments for scrubbing tanks.

The object in view is the facilitation of wringing operations under conditions conducive to the attainment of the most results at a relatively small expenditure of 20 effort.

With this and further objects in view as will in part hereinafter become apparent and in part be stated, the invention comprises certain novel constructions, combinations 25 and arrangements of parts as will be subsequently specified and claimed.

In the accompanying drawings,—

Figure 1 is a view in side elevation of an apparatus embodying the features of the 30 present invention.

Figure 2 is a top plan view thereof.

Figures 3 and 4 are fragmentary views, the same as Figures 1 and 2, but of a slightly different embodiment.

Figure 5 is a view similar to Figure 2 of a still different embodiment, the tank being omitted.

Referring to the drawings by numerals, 2 indicates a scrubbing tank which may be 40 of any conventional type, and on the upper edge of which is mounted a frame 1. The frame 1 consists essentially of a cross bar and a pair of parallel arms, the cross bar being shaped and adapted to rest upon 45 and partly enclose the upper edge of one end of tank 2, while the arms extend along and partly enclose the upper edges of the adjacent portions of the sides of the tank. 50 Journaled in the arms of frame 1 is a roller 3 which will hereinafter be referred to as the fixed roller, since, while it is revolvably mounted, it is fixed against bodily movement. Each of the arms of frame 1 is 55 formed with an arcuate track 4 terminating at its forward portion in an elongated notch 4', the upper edge of which notch is formed

by the overhanging portion of a bracket-like upward and rearward extension 3'. Pendent from the rear end portion of each arm of frame 1 is a plate 6', each of which 60 rigidly carries near its lower end a stub shaft 6''. On the stub shafts 6'' are journaled the arms of a yoke 6, in the upper ends of which arms is journaled a movable roller 5. The location of the shafts 6'' and 65 the length of the arms of yokes 6 are such as to cause the roller 5 to travel on the arc described by the tracks 4 when the yoke is swung upon its pivots 6''. To tend to cause the roller 6' to remain spaced from the 70 roller 3, the yoke 6 is counter-balanced as by being provided with an outstanding arm 7 on which is adjustably mounted the counter-balance weight 8. The connection of the arm 7 is preferably below the pivots 6''. 75 Also attached to the yoke as a further counter-balance are springs 9, 9, each connected to the yoke below the arm 7 and extending forwardly and upwardly to a point of attachment to the tank 2, each spring 9 being 80 tensioned to exert a stress on the yoke 6 tending to keep the yoke in position with the roller 5 at its rearwardmost location, that is, in the open position with respect to roller 3. It is, of course, understood that 85 a closed position of the rollers 3 and 5 is such a position as will cause the rollers to grip a mop between them and squeeze the moisture therefrom as the mop passes therebetween. The journal of roller 5 is preferably 90 extended at one end and has an attached crank 5' to enable manual rotation of roller 5 when desired. Cables 10, 10 preferably of the chain type, are attached to the arms or yoke 6 and extend upwardly and 95 forwardly beneath roller 3 and up over guiding rollers 10', 10' journaled in appropriate outstanding brackets of frame 1, the chains 10 extending down from the rollers 10' to 100 and being connected with an operating treadle 11. The treadle 11 is appropriately pivoted to the under frame of the tank 2 or its supporting truck.

In operation, the roller 5 stands normally 105 in the open position until the operator desires to wring the mop or other article to be wrung. The article is lowered from above down between the rollers 3 and 5, and then the operator places his foot on treadle 11, thus drawing upon the chains 10 and 110 moving the yoke 6 against the stress of springs 9 and weight 8 until the roller 5

firmly clamps the article between itself and roller 3. In coming to this position, the journals of roller 5 roll or slide along the tracks 4, and having reached this position 5 the rollers are either manipulated by pulling the mop upward against the resistance of the rollers or by rotating the crank 5'. As soon as this wringing operation is completed, the operator removes his foot from the 10 treadle 11 and the roller 5 automatically returns to the open position, ready for the next operation. It is to be noted that the frame 1 with the parts which it carries is adapted for easy and ready application to 15 any wringing tank already in use, it being understood, of course, that the springs 9 must be appropriately attached either to the tank or to the frame, and the treadle 11 must be pivotally mounted.

20 In Figures 3 and 4, the tank, frame, yoke, rollers and roller closing means are arranged the same as above described, and the same reference numerals have been applied. However, in this construction the counter- 25 balance weight for the yoke 6 is supplemented in its action, not by springs, but by a cable 13 which extends over a roller 14 arranged in a bracket outstanding from the middle portion of the end bar of frame 1, 30 and beyond the roller the chain 13 is provided with a handle 15 adapted for manual manipulation. The operation of the structure is identical with that above described except that when the weight 8 fails to move 35 roller 5 to its open position with sufficient celerity, the operator will grasp the handle 15 and pull upon it will swing the yoke 6 backward to the open position of the rollers.

40 In Figure 5 is shown a further modification of the invention wherein the frame 1^b is mounted upon the scrubbing tank and is slightly differently shaped from frame 1 in that in addition to enclosing the upper edge 45 portions of the tank, a plate or platform 26 is provided at one side and the tracks 4^b are not spaced apart for the full width of the tank by as much as the space occupied by the width of the plate 26. The fixed roller 16 is journaled in the frame 1^b and the movable roller 17 co-operates with respect thereto after the manner of roller 5, 50 the roller 17 being journaled in the upper ends of a yoke 6^b which is pivotally mounted in the same manner as yoke 6. Chains 55 18 engage the yoke 6 and extend to an operating treadle 19 corresponding in form and function with the chains 10 and treadle 11. Engaging the arms of the yoke 6^b sub-

stantially at the same point as do the chains 18 are chains 24 which extend rearward and 60 upward from the yoke and converge, uniting in a chain 21 which passes about guiding rollers 23 and 22, 22, and being provided at its forward end with an operating handle or grip 20. The roller 16 in this instance 65 is provided with an operating crank 5^b for rotating the roller when desired, but by preference the roller is power driven by having that journal opposite the one carrying crank 5^b extended and provided with a sprocket 70 about which is passed a sprocket chain 27 which extends to and passes about a sprocket driven by an electric motor 25. The said motor is rigidly mounted on the platform or plate 26. In this construction, the wringing operation is effected by merely turning on the current after the mop has been placed between the rollers and clamped therebetween. The clamping action is effected by 75 pressing down the treadle 19 just the same 80 as the operation of treadle 11. After a wringing operation has been completed, the operator gives a pull on the handle 20 which moves the yoke 6^b rearward and thus moves the roller 17 to the open position. While 85 the yoke 6^b is not shown counter-balanced, it obviously may be when desired.

It is apparent, of course, that the invention is susceptible of embodiment in various forms without departing in the least from 90 its spirit and scope.

I claim:—

In wringing apparatus, the combination of a frame adapted for application to a tank, a fixed roller journaled in the frame, 95 a yoke pivoted to the frame, a roller journaled in the yoke and movable therewith toward and from the fixed roller, counter-balancing means connected to the yoke and stressing the same in a direction for moving the roller carried thereby away from the fixed roller, the frame being formed with an exposed, arcuate track for each journal of the movable roller, each of said tracks terminating in an elongated guiding notch flaring 105 outward and leading from a point adjacent the respective journal of the fixed roller, and means for moving the yoke 100 against the stress of the counter-balance.

110 In testimony whereof I affix my signature in presence of two witnesses.

SIMEON C. LAWLOR.
